UNITED STATES PATENT OFFICE

158,901

COFFEE GRINDER

Richard L. Schuhmann, Louisville, Ky., assignor to American Duplex Company, Louisville, Ky., a corporation of Kentucky

Application May 21, 1949, Serial No. 2,805

Term of patent 14 years

(Cl. D55—1)

To all whom it may concern:

Be it known that I, Richard L. Schuhmann, a citizen of the United States, residing at Louisville, in the county of Jefferson and State of Kentucky, have invented a new, original, and ornamental Design for a Coffee Grinder, of which the following is a specification, reference being had to the accompanying drawing forming a part thereof.

In the drawing:

The end opposite the end seen in Figure 1 is plain except for the transverse bands near the top and bottom.

I claim:

The ornamental design for a coffee grinder, substantially as shown and described.

RICHARD L. SCHUHMAN.
